[57] CLAIM

The ornamental design for a wall attachment housing for a refrigerating machine, as shown.

DESCRIPTION

FIG. 1 is a front perspective view of a wall attachment housing for a refrigerating machine, showing our new design;

FIG. 2 is a front view of the wall attachment housing for a refrigerating machine shown in FIG. 1;

FIG. 3 is a right side view of the wall attachment housing for a refrigerating machine shown in FIG. 1;

FIG. 4 is a left side view of the wall attachment housing for a refrigerating machine shown in FIG. 1;

FIG. 5 is a rear view of the wall attachment housing for a refrigerating machine shown in FIG. 1;

FIG. 6 is an enlarged top view of the wall attachment housing for a refrigerating machine shown in FIG. 1; and,
FIG. 7 is an enlarged bottom view of the wall attachment housing for a refrigerating machine shown in FIG. 1.
